UNITED STATES PATENT OFFICE

2,455,424

PERFORATED COMBUSTION TUBE
DISTILLATE BURNER

Gabriel Z. Levine, West Hartford, Conn., assignor
to Barridon Oil Burner Corporation, Hartford,
Conn., a corporation of Connecticut

Application May 20, 1947, Serial No. 749,245

1 Claim. (Cl. 158—88)

1

The present invention relates to multiple oil burners and more particularly to improvements in the construction and operation of distillate burners.

In distillate burners in order to insure maximum efficiency and economy of operation, the burner base should be constructed so as not to leak when the oil enters the base, and the base must be capable of withstanding a heat of 1500° to 2000° F. Additionally, the vaporizing cover as well as the other parts of the burner should properly fit in order to prevent vapor or gases from leaking. Accordingly, an important object of the invention consists in providing a one-piece steel multiple burner base which is stamped to form concentric wick receiving grooves, and also circumferentially spaced raised portions between the grooves that have elongated air circulating or chimney openings. The space between the raised portions constitutes transverse or radial passages for communicating the inner and outer grooves. The bottom of these passages are positioned below the bottom of the grooves so that the wicking in the grooves will not close the flow of oil thereto.

Heretofore in burners of this type the base has been formed of grey iron castings. One of the main drawbacks of such cast iron burner bases is their porosity which allows the oil to seep through the bottom of the base. It has been found that when oil is placed in a cast iron burner base the bottom of the base is soon coated with a film of oil regardless of the high quality of the casting. Moreover, unlike pressed steel which is extremely smooth, iron castings have a rough surface into which the carbon bakes making it practically impossible to be removed. There is also a high percentage of breaking in castings due to their brittleness. Another disadvantage is that castings vary in size which leads to a consequent poor fitting of the perforated shells, the vaporizing cover and the top cover, and thus allows the gas or vapor to escape and be dissipated. Heretofore it has been impossible to make a double wick steel burner base due to the fact that steel cannot be drawn in one piece and still contain an oil inlet which allows the oil to pass from one groove to the other. Making the base of two pieces and welding them together introduces the possibility of leakage through the weld, and because of the intense heat generated, the base soon warps, causing the seam to open. Another factor is that the base is a delicate article and when it has to be welded and then machined for smoothness it makes the cost practically pro-

2

hibitive. By stamping the steel burner base in accordance with the present invention, leakage is eliminated since the base is of one-piece construction. Further, it will not allow oil to seep through because unlike cast iron, steel is not porous, nor will it carbonize as quickly as cast iron due to its surface smoothness. As the steel bases are stamped, they will be of uniform size and shape, so that the shells, top covers and vaporizing covers will fit properly in position and thus prevent the wasteful escape of gas.

Another disadvantage of a cast iron base burner is that the radial passage or portholes in such a base which communicate the inner and outer wick receiving grooves, are closed thus rendering it difficult to clean and remove the carbon formed therein. Therefore a further object of the invention consists in providing a removable one-piece vaporizing cover which fits over the chimney and closes the radial passages that communicate the inner and outer wick receiving grooves so as to allow these passages to be easily cleaned. The removable vaporizing cover is provided with spaced depending flanges that mate snugly with the chimney openings and thus preclude the escape of vapor therefrom. Moreover the cover is so shaped and constructed as not to interrupt the position of the wicking or require the flame to jump across a gap.

Other objects and advantages of the invention will become apparent from the following description when taken in conjunction with the accompanying claim and drawings.

Referring to the drawings in which are shown several preferred embodiments of the invention:

Figure 1 is a plan view of the improved multiple burner with the vaporizing cover mounted thereon.

Figure 2 is a view similar to Figure 1 with the vaporizing cover removed.

Figure 3 is a vertical sectional view taken substantially along the line 3—3 of Figure 1.

Figure 4 is a detailed longitudinal sectional view of the cover removed from the burner.

Figure 5 is a sectional view taken substantially along the line 5—5 of Figure 2.

Figure 6 is a sectional view taken substantially along the line 6—6 of Figure 3.

Figure 7 is a plan view of the burner base associated with an adjustable support, and

Figure 8 is a sectional view taken substantially along the line 8—8 of Figure 7.

Referring to the drawings in which like numerals indicate like parts in the several views, 10 designates the burner base of a distillate burner,

and is stamped from a blank of steel to provide an inner cylindrical wall 11 and an outer cylindrical wall 12 (Fig. 3), each of which is laterally offset as at 13 to provide a shoulder which terminates in an upwardly extending annular flange 14. The bottom of the base between the inner wall 11 and the outer wall 12 is stamped circumferentially to form three spaced raised portions 15, 16 and 17 (Fig. 2), each of which has an elongated arcuate chimney opening 18 that is enclosed by a flange 19 extending upwardly from the top of its associated segmental portion. The flanges 19 are spaced from the inner and outer sides of the segmental top portions to form ledges or shoulders 20 which align with the shoulders 13 on the inner and outer walls 11 and 12. The segmental raised portions 15, 16 and 17 are spaced from the inner and outer walls 11 and 12 of the burner to form an inner annular groove or channel 21 and a concentric outer groove 22 that receive the burner wicks 23 and 24. These wicks may be made of asbestos or other suitable non-flammable material. The inner and outer wick receiving grooves 21 and 22 communicate with each other through three spaced transverse or radial passages 25 located between the adjacent segmental portions 15, 16 and 17 and stamped from the burner base so that the annular wick receiving grooves 21 and 22 are raised above the bottom of the passages 25 (Fig. 6). A depending threaded tubular nipple 26 extends downwardly and outwardly from the bottom of one of the passages 25 (Fig. 3) so as to constitute means for supplying fuel to the burner base 10. Additionally, the bottom of the burner base may have connected thereto as at 27 a threaded bolt 28 for detachably securing the burner base to a suitable support, not shown.

An annular one piece cover plate 29 is arranged to be removably mounted on the top of the raised segmental portions 15, 16 and 17 and is formed with spaced arcuate openings or slots 30 that register with the chimney openings 18 and are of substantially the same width and length as the chimney openings. The top of the cover plate 29 adjacent each of the openings 30 extends downwardly to form flanges 30' (Figure 4) in sealing engagement with the inner sides of the flanges 19 on the raised portions 15, 16 and 17, and which prevent turning of the cover plate relative to the burner. The unperforated portions 31 of the cover between the slots 30 extend over the transverse passages or ports 25 so as to close the same and prevent gas or vapor from escaping upwardly from these passages. The cover 29 also has spaced depending inner and outer flanges 32 and 33 which are arranged to overlap and snugly engage the adjacent flanges 19 of the chimney openings 18 when the burner is assembled. Thus, it will be seen that the cover 29 fits the burner base tightly, and that the flanges 30' coact with the flanges 32 and 33 to provide vapor sealing means for preventing escape of the oil gases into the chimney openings or air vents. Four concentric perforated shells or sleeves 34, 35, 36 and 37 (Fig. 3) are arranged to be removably mounted on the burner and have their lower ends supported by the shoulders 13 and 20 and are suitably spaced to form the combustion chambers 38 and 39 which are positioned between the annular air opening 40 that communicates at its lower end with the chimney openings 18 of the burner. A lid 41 having a handle 42 may be removably mounted on the top of the shells and preferably is formed with transversely spaced

shoulders 43, 44 and 45 that receive the adjacent ends of the shells so as to retain the latter in a fixed position. When the burner is assembled the uninterrupted spaced annular wicks 23 and 24 fit within the annular grooves 21 and 22 and rest on the bottom of the burner. As the spaced radial passages 25 have their bottoms positioned below the grooves 21 and 22 the portions of the wicks 21 which pass across the radial passages 25 are spaced from the bottom thereof to form a clearance or opening 46 (Fig. 6), so that the wicking will not interrupt or close the free flow of oil to the annular grooves 21 and 22. The flanges 14 and 19 constitute retaining means for maintaining the lower ends of the perforated shells in position. The lid 41 has arcuate openings 47 which register with the openings 18 and 30 so as to allow the flame to issue from the burner. As shown, the diameter of the lid 41 is such as not to cover the top of the outer chamber 38 so that the same communicates with the atmosphere. Within the inner wall 11 of the burner is provided a central air opening 48 that communicates through the perforated shell 34 with the chamber 39. The one-piece steel distillate burner it will be seen may be efficiently and economically used so as to insure complete combustion and maximum heat without wasting or dissipating the fuel and is particularly suited for use in range burners, cooking stoves, water heaters, circulating heaters, radiant heaters and the like.

In operation when the parts of the multiple burner are assembled they will assume the position as shown in Figure 3. Fuel such as coal oil or the like enters the bottom of the burner through the supply nipple 26 which communicates with one of the transverse or radial passages 25 so as to thoroughly soak the wicking. The flame is then applied to the wicking. The burner soon becomes heated and the oil therein distills into a gas and combines with the oxygen of the air circulating through the chimney openings 30, the annular passage 40 and the opening 48 that communicate with the combustion chambers 38 and 39 through the perforations in the shells 35 and 36, so as to intimately mix with the gas and form a blue flame.

The width and depth of each of the three transverse passages or portholes 25 is such as to allow an even and fast distribution of the oil to the inner and outer wick receiving grooves 21 and 22. Should for any reason one of the passages 25 become clogged because of carbonization, oil will be distributed to the grooves through the remaining opening passages. The elongated chimney openings 18 insure a proper amount of air to circulate from the bottom of the burner into the air passage 40 thus resulting in proper combustion and maximum heat. The annular grooves 21 and 22 are sufficiently wide as to permit easy insertion of the wicks 23 and 24 and the free flow of oil. As the bottom of the passages 25 are lower than the bottom of the annular grooves 21 and 22 the wicks will not close these passages but rather will form the space 46 (Fig. 6) so as to allow the oil to be delivered uninterruptedly to the grooves. The removable cover 29 rests on top of the segmental raised portions 15, 16 and 17 and the opening 30 therein register with the chimney openings 18 and the unperforated portions 29 of the cover extend over and close the top of the transverse passages 25 so as to prevent vapor from escaping from these passages. It will be noted that the cover is circular and does not

have any outwardly extending portions or ribs which would interrupt the circumferential position of the wicking and the flame and thus require the wick to be made in sections and the flame to jump across a gap. The depending flanges 32 and 33 of the cover snugly engage the flanges 19 of the elongated chimney openings 18 in order to prevent the escape of vapor and the release of objectionable odors and streaky flames. The cover 29 is readily removable so as to permit convenient access to the burner base to clean the same.

Thus it will be seen that simple, efficient and positive means are provided which includes a multiple burner having a one-piece steel base stamped to form the wick receiving grooves, air chimneys and transverse fuel supply passages, so as to insure a uniform distribution of the oil to the inner and outer grooves and the wicks therein and in which means are provided for preventing the wicking from closing the oil supply passages. Additionally, a removable one-piece cover is associated with the burner base so as to facilitate cleaning and prevent the escape of vapors from the burner. The area of the chimney openings 18 is such as to insure a sufficient circulation of air which upon mixture with the gases produces a proper combustion and maximum heat. As the removable cover 29 rests on top of the segmental raised portions 15, 16 and 17 so that the flanges 32 and 33 snugly engage the adjacent flanges 19 of the chimney openings, means are provided for preventing the escape of vapor and insure the flame issuing from the grooves and through the perforated shells and the spacing in the lid 41 without danger of any vapor leaking out or being dissipated.

In Figures 7 and 8 there is shown a support for the burner base 10 which preferably includes a pedestal 49 that may be in the form of a steel pipe or the like, that extends upwardly from the floor or other supporting base member. A substantially L-shaped bracket or member 50 is interposed between the pedestal 49 and the bottom of the burner base 10. The bracket member 50 has a depending tubular portion or sleeve 51 that is arranged to rotatably receive the upper end portion of the standard 49 and may be secured thereto in any desired rotatable position by the set screw 52. A flat horizontal portion or arm 53 extends inwardly from the top of the tubular portion 51 of the bracket member and has an elongated slot 54. To the underside of the burner base 10 is secured a mounting plate or strap 55 that may be welded as at 56 to the bottom of the base 10 and has a portion 57 extending diametrically across the center of the opening 48. The plate 55 adjacent the center of the opening 48 has an aperture 58 arranged to register with the elongated opening 54 in the arm 53, and a threaded clamping bolt 59 extends through the aperture 58 and the slot 54 and is secured thereto by the nut 60. The standard 49 is offset relative to the center of the burner base and preferably is positioned as shown in Figure 8 so that it will not interfere with the free circulation of the air through the opening 48. The tubular portion 51 of the bracket 50 is rotatably mounted on the standard 49 so that the burner may be moved

in any desired horizontal position by the actuation of the set screw 52. The plate 55 is adjustably connected to the arm 53 substantially centrally of the burner base so as to impart the desired rigidity to the burner installation when the parts are set up. Thus it will be seen that the burner base may be adjusted horizontally relative to the pedestal 49 through the set screw 52 and laterally relative to the pedestal through the bolt 59 and the elongated slot 54 in the arm 53.

It is to be understood that the forms of the invention shown and described are merely illustrative of preferred embodiments and that such changes may be made as fall within the purview of one skilled in the art without departing from the spirit of the invention and the scope of the appended claim.

I claim:

1. A distillate multiple burner including a one piece stamped steel base having a central opening and provided with inner and outer annular walls extending upwardly therefrom, said walls having laterally offset aligned shoulders and terminating in upwardly extending annular flanges, the bottom of the base between the inner and outer walls having circumferentially spaced raised arcuate portions provided with elongated chimney openings, each of said openings being enclosed by an upwardly extending flange spaced from the opposite sides of the top of its raised portion to form supporting shoulders in horizontal alignment with the shoulders on the inner and outer walls, said raised portions being spaced from the inner and outer walls to form with the bottom of the burner an inner annular groove and a concentric outer groove, the space between adjacent raised portions forming radial passages for communicating the inner and outer grooves with each other, the bottom of said radial passages being depressed to be positioned below the bottom of the grooves, wicks in said grooves and spaced from the bottom of said passages to allow the free flow of oil from the passages into the grooves, a removable cover plate spaced from said inner and outer annular walls and having spaced depending flanges overlapping and in vapor sealing engagement with the flanges on said raised portions, said plate extending over said radial passages to prevent escape of vapor therefrom and having arcuate slots provided with depending flanges in vapor sealing engagement with the inner side walls of said chimney openings, means for supplying oil to said base, and concentric spaced perforated shells mounted on said shoulders so as to be firmly supported to the base.
